UNITED STATES PATENT OFFICE.

GEORGE MILLER AND CHARLES B. MILLER, OF PHILADELPHIA, PA.

IMPROVEMENT IN THE MANUFACTURE OF CONFECTIONERY.

Specification forming part of Letters Patent No. **108,505**, dated October 18, 1870.

To all whom it may concern:

Be it known that we, GEORGE MILLER and CHARLES B. MILLER, of Philadelphia, in the county of Philadelphia and State of Pennsylvania, have invented a new and useful Improvement in Packing Confectionery; and we do hereby declare the following to be a full, clear, and exact description of the same, reference being had to the accompanying drawings, making a part of this specification, in which—

Figure 1 is a perspective view, a portion of the wall and cover being removed. Fig. 2 is a cross-section.

The object of this invention is to provide for use a new and improved method and means of packing confectionery and small gift articles; and the invention consists in the arrangement of the packing-box, its compartments, and the materials to be packed, as hereinafter set forth.

In the drawings, A A' are a box and cover, the flanges of the latter being made wide enough to cover the whole side of the former, so that the cover completely incases the box, only the bottom of the latter being visible. In this box we pack the materials as follows: First, for example, we place in the bottom of the box a layer of nuts or confectionery, *n*, upon which we place a removable pasteboard cover, *e*, hav-

ing a little loop or tag at the center, by which it can easily be handled. We then place on this cover a set of jewelry or other attractive or valuable gift, *g*, and we place over this another cover, *e'*, similar to the former. The space above this cover we fill full of confectionery, gay-colored candies, &c., so as entirely to conceal the cover *e'*, and lead any person, on opening the box, to suppose it filled merely with candies. We place tissue-paper over the candies, one or more sheets, attached at the side edges to the walls of the box, or not, as may be thought desirable. The whole forms a very neat handsome box of confections, &c., particularly suitable for a Christmas-gift box.

Having thus described our invention, what we claim as new, and desire to secure by Letters Patent, is—

1. The method of packing confectionery, &c., as herein described and shown.
2. A box of confectionery, jewelry, or other similar articles, arranged, as described, in layers, one over the other, and separated by intervening covers of pasteboard, as described.

GEORGE MILLER.

CHARLES B. MILLER.
